TRAVELING SHEAVE BLOCK

Lester C. Black, Bakersfield, Calif.

Application May 12, 1947, Serial No. 747,382

2 Claims. (Cl. 254—192)

1

This invention relates generally to traveling sheave blocks of the type suitable for use in oil well drilling.

In oil well drilling operations it is common to provide the top of a derrick with a crown block, which is used in conjunction with a multi-sheave traveling block. In order to facilitate manipulation of the traveling block, particularly during the uncoupling of casing or tubing sections, it is common to utilize so-called spring hooks or clevises which connect between the traveling block and the work. Such devices enable limited vertical movement of the work without winding up or playing out the hoisting cable. Hooks and clevises of the spring type have the disadvantage that when attached to a traveling block, the overall vertical dimensions of the assembly are considerably increased, thus limiting the vertical hoisting distance for a given derrick installation.

It is an object of the present invention to provide a new traveling sheave block construction which incorporates spring means, while eliminating the necessity of utilizing a conventional spring hook or clevis.

A further object of the invention is to provide a traveling block which inherently incorporates as a part of its assembly a spring means enabling relative movement between the sheave assembly of the block and the work attaching hook.

Another object of the invention is to provide a traveling sheave block of the above character which is relatively compact with respect to its dimensions, and which can be used to advantage in connection with deep well drilling.

Another object of the invention is to provide a traveling sheave block constituting an improvement to the traveling block disclosed in my Patent 2,052,075, granted August 25, 1936.

Additional objects of the invention will appear from the following description in which the preferred embodiment has been set forth in detail in conjunction with the accompanying drawing.

Referring to the drawing:

Figure 1 is a side elevational view illustrating a traveling sheave block incorporating the present invention.

Figure 2 is a cross-sectional detail taken along the line 2—2 of Figure 1.

Figure 3 is a cross-sectional view taken along the line 3—3 of Figure 1.

Figure 4 is a side elevational view like Figure 1 but illustrating another embodiment of the invention.

Figure 5 is an elevational view looking toward the right hand side of Figure 4.

Figure 6 is an enlarged detail in section illustrating the manner in which a plurality of springs are mounted in the upper portion of the block,

2

to take the place of the single spring of Figures 1 to 3 inclusive.

Figure 7 is a cross-sectional view taken along the line 7—7 of Figure 6.

That form of the invention illustrated in the drawing consists generally of a plurality of cable sheaves 10 which are preferably ring shaped as disclosed in said Patent 2,052,075. The mounting structure for the sheaves includes a rigid drum 11 which is fitted with bearing rings 12 and spacer rings 13 and 14. Bearing rollers 16 are interposed between the rings 12 and cooperating bearing rings 17 fitted within the sheaves 10. Clamping rings 18 and 19 are fitted upon the end portions of the drum 11. Ring 18 is recessed to seat upon a flange 21 formed on the drum, while ring 19 is recessed to receive the flange 22 of a retaining ring 23. Ring 23 is secured as by means of bolts 24 to the internal flange 26 of the drum.

In addition to the parts described above the mounting structure for the sheaves includes the side plates 28 and 29 which have central openings and are seated upon the rings 18 and 19 as illustrated. The upper ends of these plates above the sheaves are attached together by bar 31, which is removably secured to the plates as by means of pins 32. Projecting lugs 33 carried by the ends of the bar engage recesses 34 provided in the upper edges of the plates 28 and 29, thereby providing non-pivotal rigid connections.

Filler plates 36 and 37 are attached to the outer faces of the plates 28, 29. These filler plates extend in a general vertical direction and their opposed parallel edges are spaced apart to form the vertically extending guideways 38, 39.

Cooperating with the assembly described above there is a frame structure which serves to carry a work attaching hook. This frame structure includes the side plates 41 and 42 which are slidably accommodated within the guideways 38, 39. The lower ends of the plates 41 and 42 are connected by the clevis bar 43 which in turn serves to carry a hook 44. This hook may be any one of a number of conventional types, but for deep well drilling it is desirable to utilize a triple hook device, including the main lower hook 46, and the smaller side hooks 47. The clevis bar 43 is shown attached to the lower end of plates 41 and 42 by pins 48, the plates being provided with webs 49 for this purpose. Plate 42 is shown provided with an opening normally closed by cover 45, thereby enabling access to the interior of the drum 11 for lubrication or for facilitating repairs.

The upper ends of the plates 41 and 42 are connected by the deckle 49 (Figure 3). The attachment in this instance can likewise be provided by the removable pins 51. Interposed between the deckle 49 and the bar 31, there is a

compression spring 52. The upper end of this spring is shown seated over a stud 53 carried by the deckle, in order to prevent its lateral displacement.

Because the compression spring is interposed between the mounting structure for the sheaves and the frame structure which carries the hook 44, and because the two structures are slidable with respect to each other, the frame structure is always urged toward its uppermost position relative to the sheaves. Assuming that the sheaves engage the lower ends of cable loops, the load applied to the hook 44 is directly opposed by the spring 52, and therefore as the load is increased, a substantial amount of relative movement may occur between the sheaves and the work hook. In actual practice suitable limiting means are provided to restrict such relative movement between definite limits. Thus in the block described, when the frame structure moves upwardly with respect to the mounting structure of the sheaves the upper ends of lugs 48 are ultimately brought into abutment with the lower edges 54 of the plates 28, 29 (Figure 3). Similarly when the frame structure is moved downwardly with respect to the sheaves the lower edges of the mounting ears 56 for the pins 51 are brought into engagement with the lugs 33 on the bar 31.

Operation of the traveling block described above can be reviewed as follows: In normal operation the traveling block is used with a derrick crown block, and a hoist cable is reeved between the crown block and the traveling block whereby the sheaves of the traveling block normally engage the lower ends of depending cable loops. Hook 44 is attached to the work, whereby when a weight or pull is applied to the hook, such force is applied directly to the compression spring 52. Relative vertical movement may occur between the hook and the sheaves, by virtue of the sliding engagement between the frame structure which carries the hook and the mounting structure which carries the rotating sheaves. Thus during certain operations, such as the uncoupling of tubing sections, compression and expansion of spring 52 together with relative sliding action makes possible a latitude of vertical movement of the hook and the work, without corresponding movement of the traveling block sheaves or of the hoist cable.

The embodiment of the invention illustrated in Figures 4 to 7 inclusive makes use of a plurality of compression springs in place of the single compression spring 52 of Figures 1 to 3 inclusive. The block in this instance consists of a plurality of ring-like sheaves 61 mounted by roller bearing assemblies upon the drum 62. The ends of the drum are attached to the side plates 63, corresponding to the side plates 28 and 29 of Figures 1 to 3. Filler strips 64 (Figure 4) are attached to the side plates 63 and provide vertically extending guideways 66 for slidably accommodating the vertically extending plates 67.

The upper ends of plates 63 are attached to the connecting casting 68, which is provided with a plurality of studs 69 for seating and retaining the lower ends of compression springs 70. The upper ends of plates 67 are held together by the pin 72, which also serves to attach the deckle 73. The deckle is provided with downwardly faced shoulders 74 and studs 76 to provide seats for the upper ends of compression springs 70. The hook 77 carried by the lower end of the block, is shown supported by a swivel bearing 78, which

is in turn is carried by a casting 79 which connects to the lower ends of the plates 67.

The embodiment of the invention illustrated in Figures 4 to 7 inclusive operates in the same manner as the previously described embodiment. Relative movement may occur between the hook and the sheaves, and such movement is accommodated by the sliding of side plates 67 within the guideways 66, and by compression and expansion of the springs 70. By the use of multiple compression springs and a mounting as described it is possible to obtain a relatively high total spring force without utilizing a single spring of excessive size.

Advantages of my construction will be apparent from the above. The spring is incorporated as an inherent part of the traveling block without materially increasing the dimensions of the same. Incorporation of the spring means as an inherent part of the block assembly does not in any way interfere with the utility or adaptability of the block. All of the various parts of the block can be readily disassembled for making repairs or replacements.

I claim:

1. In a traveling sheave block construction, a plurality of sheaves disposed side-by-side and adapted to engage the lower ends of depending cable loops, means including a rigid drum extending axially within the sheaves and serving to form a journal mounting for the same, side plate rigidly attached to the ends of the drum, spaced filler plates attached to the outer faces of the side plates and forming with the side plates a pair of outwardly faced parallel guideway recesses, a frame structure, the frame structure including a pair of laterally spaced vertically extending side plates slidably retained within said guideway recesses, a member serving to interconnect the upper end portions of said first mentioned side plates, another member serving to interconnect the upper ends of said last mentioned side plates, and a compression spring interposed between said members serving to resist downward movement of the frame structure relative to the sheaves.

2. In a traveling sheave block, a plurality of side by side sheaves, rigid means forming a journal mounting for the sheaves, spaced parallel side guards rigidly attached to said mounting, each guard comprising plates assembled to form an outwardly faced guide recess extending the length of the same, the two recesses being parallel, a frame structure, said structure including a pair of spaced parallel side plates slidably disposed in said guide recess and a member serving to connect the upper ends of said side plates, means attached to the lower end of the frame structure for attaching work to the block, another member serving to connect the upper ends of the guard plates, and spring means interposed between said members, said spring means serving to resist downward movement of the frame structure relative to the sheave assembly.

LESTER C. BLACK.
